SIZE-GRADING MECHANISM

Lewis R. Allen, Carbondale, Ill.

Application December 10, 1931, Serial No. 580,031

5 Claims. (Cl. 209—307)

This invention relates to improvements in size-grading mechanism, and more particularly to such mechanism for separating out the various sizes of fruits, vegetables or the like, and has 5 among its objects, the production of such a mechanism that will be simple and sturdy in construction, neat in appearance, durable, and efficient and satisfactory for use wherever found applicable.

10 Another object of my invention is to provide a separating belt for such a mechanism, and which will have no points or projections extending therefrom and which might pierce or otherwise damage or injure the fruit or similar soft 15 material passing thereover.

Another object of my invention is to form such a belt of a plurality of ring elements having continuously extending eyes at the sides thereof, and links through the eyes of adjacent ring elements 20 to interconnect said elements together, with said eyes in abutment, to thereby form true and substantially unbroken ring openings between the adjacent elements.

Still another object of my invention is to so construct said belt of such ring elements and interconnecting links, that the belt will be sufficiently flexible to be driven over sprocket wheels or similar devices for driving, and that said belt will flex or pivot both longitudinally and laterally in 30 true straight lines, to thereby enable the ring elements to present their top surfaces in smooth unbroken contours and not with some of the elements askew.

Many other objects and advantages of the construction herein shown and described will be obvious to those skilled in the art to which this invention appertains, from the disclosures herein given.

To this end my invention consists in the novel 40 arrangement, construction and combination of parts herein shown and described, and the uses mentioned, and more particularly pointed out in the claims.

In the drawing, wherein like references indicate like or corresponding parts throughout the views,

Figure 1 is a top plan view of my improved mechanism;

Figure 2 is an enlarged detail view of a section 50 of the belt thereof; and

Figure 3 is an end cross-sectional view of the belt as it appears while passing over one of the drive wheels.

Referring more particularly to the drawing, 55 wherein I have illustrated a preferred embodi-

ment of my invention, A represents the framework of the mechanism, the same comprising generally, a hopper or the like into which the fruit, vegetables or the like is placed as at 1, with a preferably traveling separator belt B forming the 60 bed of the same. This belt may be driven with any suitable means as by sprocket wheels 2 and 3, the actuating or driving handle being indicated at 4. The fruit passes through the openings provided in the separator belt B and onto a conveyor, 65 chute or other suitable means therebelow and from whence it is conducted to the packing rooms or the like, the larger fruit passing along the belt and discharged therefrom at the far end thereof.

Obviously, where the objects being graded as to 70 size are fruit or the like, it is highly important that the same be handled with care so as to avoid puncturing, abrading, crushing or injuring them in any other manner which would make them less desirable and hence decrease their worth. 75 To this end, I have taken great care that the belt will present a smooth, unbroken surface to the fruit passing therewith and thereover, and insure that some of the elements out of which the belt is formed shall not set askew during its 80 travel, and that although the elements will have movement relatively of one another to accomplish their purpose, yet there will be substantially no play between the various elements and their interconnecting fasteners.

85 The belt B is composed of the plurality of the separate individual ring elements interconnected by fastening links to form an endless member. Each ring element consists of a main ring portion 5 of the size desired for grading a particular commodity, such as oranges, apples, or the like, this ring opening 5 being continuous throughout its circumference.

90 Projecting laterally from each of the ring elements are two pairs of diametrically opposed eyes 6—6 and 7—7, respectively, each of said eyes being formed with a cross-bar or eye-bar at its outermost side, spaced radially from the ring portion 5, the bars on the eyes 6—6 being indicated as 95 8 and 9, and the bars on the other pair being similarly represented. It is to be noted at this point, that the bars are all not of the same width, but that upon the contrary, the bars 9—9 adjacent one another are wider than the other bars 8—8 and are wider than the thickness of the element 100 thereat, for a purpose to be more clearly herein-after described.

105 Side arms 10 extend from the periphery of the ring portion 5 of the ring elements extending arcuately in both directions and terminating at 110

the cross bars 8 and 9 to form the eyes 6 and 7 therewith. These side arms extend for substantially a complete quarter circle so that when the ring elements are juxtaposed, as in the drawing, 5 the cross bars of adjacent elements will abut one another and leave no openings or sharp projections therebetween to engage the fruit that is intended to pass thereover.

Links 11 are positioned over the eye-bars of 10 adjacent ring elements so as to interconnect said adjacent elements to form said separator belt, holding these elements in position to form the true, full circular, continuous rings therebetween and through which the fruit may pass without 15 injury. These links are preferably made of wide metal strips, the width of the strips being substantially equal to that of the eyes (between the outermost ends of the side arms) so as to pass therethrough without play therebetween, said link 20 closely encircling said eye-bars as shown, and the ends of the links brought up into abutment across the width of the material.

The elements are so placed in juxtaposition that the wide bars 9—9 of one element are adjacent the narrower bars 8—8 of the adjacent element, so that each link will embrace a wide bar and a narrow bar of the adjacent elements. Obviously, inasmuch as the bars 9—9 are wider than the thickness of the ring elements thereat, those 30 portions of the link that embrace the wide bars may not have pivotal movement relative thereto, but will move therewith and as part thereof, while the portion of the link that embraces the narrower bars permits of pivotal movement therebetween.

35 In this way, the belt will have its necessary amount of flexibility, so as to permit it to function efficiently, and yet will always present a smooth surface to the fruit thereon, and some of the elements will not be askew relative to the others. The elements will be in abutment with one another to further insure this smooth, unbroken surface, and there will be no projecting ends, prongs or corners that could injure the fruit 40 passing therewith, and the elements will have no lateral play therebetween.

Further, the belt will pivot or bend across its width, as well as longitudinally thereof, in true and straight lines, all of the wider bars 9—9 being to one side of the pivotal axes, and the 50 narrower bars to the other side of these axes. The links will be limited in their pivotal movement, to movement only relatively of the elements connected thereto with its narrower bar, and hence there will not be the same likelihood of the 55 ring elements getting askew and in different various planes as if the links were pivotally movable at both its ends where they are attached to these elements.

Having thus described my invention, it is obvious that various immaterial modifications may be made in the same without departing from the spirit of my invention; hence I do not wish to be understood as limiting myself to the exact form, arrangement, construction and combination of parts herein shown and described, or uses mentioned, except as limited by the state of the art to which this invention appertains, or from the 60 claims hereto appended.

What I claim as new and desire to secure by 70 Letters Patent is:

1. A separating mechanism having a plurality of separator elements; and links for interconnecting them to form a belt, each of said elements having a central ring and two pairs of diametrically opposed straight bars of substantially equal length, the bars of adjacent elements abutting one another and one being circular and the other substantially rectangular in cross-section, 80 one pair of adjacent bars of each element being wider than its thickness thereat, and said elements juxtaposed so that said wider bars of one element will abut a narrower bar of the adjacent element, each of said links being engaged closely about a narrow and a wide bar of a pair of adjacent elements.

2. A separating mechanism having a plurality of elements; and links of relatively thin material for interconnecting them to form a belt, each of said elements having a ring and two pairs of diametrically opposed eyes, the eyes of adjacent elements abutting one another, the side arms of each eye being straight and extending continuously from the ends of its bar to the ends of the adjacent bars, one pair of adjacent bars of each element being wider than its thickness and of non-circular cross section, and said elements juxtaposed so that said wider bars of each element will abut a narrower bar of the adjacent element, each of said links substantially closely encircling and engaging a narrow and a wide bar of adjacent elements, whereby said links are substantially flush with the top of said elements and are held against rotation relatively of one of each pair of adjacent interconnected elements.

3. A separating mechanism having a plurality of ring elements; and links for interconnecting said elements to form a belt, each of said elements having a plurality of link-receiving straight bars, all of equal length but one of said bars being wider than the thickness thereat and of substantially rectangular shape in cross-section, said links substantially closely encircling and engaging a wider bar of one element and one of the narrower bars of the adjacent element.

4. A separating belt comprised of a plurality of ring elements, each of which has two pairs of diametrically opposed bars extending therefrom, two of the adjacent bars being of rectangular cross-section and wider than the other two bars and than the thickness of the element, said elements being positioned with the wider bar of one element juxtaposed to the narrower bar of the other element; and links snugly engaged about the said juxtaposed bars of adjoining elements to hold them together and prevent relative rotation 120 of said links about said wider bars.

5. A separating belt comprised of a plurality of ring elements each of which has two pairs of diametrically-opposed link-receiving bars extending therefrom, two adjacent bars of each element being of rectangular cross-section and wider than the thickness of said elements, and said elements being juxtaposed so that said wider bars of one element will abut the narrower bars of the adjacent element; and links substantially closely encircling and engaging juxtaposed pairs of bars to interconnect said elements together.

LEWIS R. ALLEN.
